CLAIM

The ornamental design for a wire rack shelf, as shown and described.

DESCRIPTION

FIG. 1 is a top, front, and right side isometric view of the wire rack shelf according to a first embodiment of the present invention.

FIG. 2 is a top plan view thereof according to the first embodiment.

FIG. 3 is a front elevation view thereof, the rear view being identical according to the first embodiment.

FIG. 4 is a right side elevation view thereof, the left side view being identical according to the first embodiment.

FIG. 5 is a bottom plan view thereof according to the first embodiment.

FIG. 6 is a top, front, and right side isometric view of the wire rack shelf according to a second embodiment of the present invention.

FIG. 7 is a top plan view thereof according to the second embodiment.

FIG. 8 is a front elevation view thereof, the rear view being identical according to the second embodiment.

FIG. 9 is a right side elevation view thereof, the left side view being identical according to the second embodiment.

FIG. 10 is a bottom plan view thereof according to the second embodiment.

FIG. 11 is a top, front, and right side isometric view of the wire rack shelf according to a third embodiment of the present invention.

FIG. 12 is a top plan view thereof according to the third embodiment.

FIG. 13 is a front elevation view thereof, the rear view being identical according to the third embodiment.

FIG. 14 is a right side elevation view thereof, the left side view being identical according to the third embodiment; and,

FIG. 15 is a bottom plan view thereof according to the third embodiment.
